UNITED STATES PATENT OFFICE

136,880

DESIGN FOR A SMOKING PIPE

Charles Rubin, Bronx, N. Y.

Application October 7, 1942, Serial No. 108,447

Term of patent 14 years

To all whom it may concern:

Be it known that I, Charles Rubin, a citizen of the United States of America, residing in the Borough of Bronx, city of New York, county of Bronx, and State of New York, have invented a new, original, and ornamental Design for a Smoking Pipe, of which the following is a specification, reference being had to the accompanying drawing, forming a part thereof.

Figure 1 is an elevational view of a smoking pipe showing my new design.

Figure 2 is a transverse horizontal sectional view as might be seen from the plane 2—2.

Figure 3 is a top plan view of Figure 1.

Figure 4 is a bottom plan view of Figure 1.

Figure 5 is a fragmentary vertical sectional view as might be seen from the plane 5—5 on Figure 3.

Figure 6 is a vertical sectional view as might be seen from the plane 6—6 on Figure 1.

Figure 7 is an end elevational view as might be seen from the left of Figure 1.

The dominant features of my design reside in the portions shown in full lines in the drawing.

The characterizing feature of my design for the smoking pipe illustrated resides in the oval shape of the bowl with its greater transverse dimension in the direction of the pipe stem and having smoothly curved outer surfaces as shown.

I claim:

The ornamental design for a smoking pipe, as shown and described.

CHARLES RUBIN,
